UNITED STATES PATENT OFFICE.

CHARLES BOOZ, OF BUFFALO, NEW YORK, ASSIGNOR TO HENRY M. BIRGE, OF SAME PLACE.

DESIGN FOR WALL-PAPER.

SPECIFICATION forming part of Design No. 26,138, dated September 29, 1896.

Application filed August 24, 1896. Serial No. 603,797. Term of patent 3½ years.

To all whom it may concern:

Be it known that I, CHARLES BOOZ, a citizen of the United States, residing at Buffalo, in the county of Erie and State of New York, have invented and produced a new and original Design for Wall-Paper, of which the following is a specification, reference being had to the accompanying drawing, showing a part thereof.

- 10 The design consists of an arrangement of sprays of roses and leaves and small sprays of grass placed irregularly over the surface of the paper, as represented in the accompanying drawing.
- 15 The border for the said design consists of an upright vase-like ornament filled with sprays of roses, leaves, and grass, with small panels formed by light diverging lines, with sprays of roses in the center of said panels and arranged in a horizontal line, and an ornamental band below said panels, as shown in the drawing.

What I claim is—

1. The design for wall-paper herein shown and described.
2. In the design for wall-paper the border herein shown and described.

Witness my hand this 10th day of August, 1896.

CHARLES BOOZ.
